Primary Examiner—Jeffrey Asch

(57) **CLAIM**

The ornamental design for a wire-wrap/unwrap hand tool, substantially as shown and described.

DESCRIPTION

FIG. 1 is a left side view of a first embodiment of a wire-wrap/unwrap hand tool according to the invention; FIG. 2 is a top plan view of the tool of FIG. 1; FIG. 3 is a bottom plan view of the tool of FIG. 1; FIG. 4 is a plan view of the front of the tool of FIG. 1, taken from the left side of FIG. 1; FIG. 5 is a plan view of the rear of the tool of FIG. 1, taken from the right side of FIG. 1; FIG. 6 is a plan view of the tool of FIG. 1 is taken from the right side, the side opposite to the view of FIG. 1; and, FIG. 7 is a view similar to that of FIG. 1 but of a second embodiment. The only difference between the two embodiments is that the end of a battery shown protruding from the bottom of the gun handle of FIGS. 1-6 has been replaced by a line cord in FIG. 7. Otherwise, the body of the gun is identical.
